J. NEWELL

PAVEMENT

Filed July 11, 1922

Inventor:
John Newell,

By Frederick V. Winter

Atty.

UNITED STATES PATENT OFFICE.

JOHN NEWELL, OF SCARSDALE, NEW YORK.

PAVEMENT.

Application filed July 11, 1922. Serial No. 574,132.

To all whom it may concern:

Be it known that I, JOHN NEWELL, a citizen of the United States, residing at Scarsdale, in the county of Westchester and State 5 of New York, have invented certain new and useful Improvements in Pavements, of which the following is a full, clear, and exact specification.

This invention relates to pavements for 10 side-walks, lawn-walks, floors, stairways, and the like, and it has for its object to provide an improved portable pavement which can be made in blocks of various dimensions and shapes, shipped from the place where 15 they are made to the place they are to be laid, and put down at little expense. When it is desired to change the position of the walk or pavement, the blocks may be readily taken up and relaid in the new location.

20 Other objects will appear as the description proceeds.

The invention will be first hereinafter described in connection with the accompanying drawings, which constitute part of this 25 specification, and then more specifically defined in the claims at the end of the description.

In the accompanying drawings, wherein 30 similar reference characters are used to designate corresponding parts throughout the several views:—

Figure 1 is a plan view of two pavement blocks constructed in accordance with this invention, the one to the left being shown 35 without the concrete and the one at the right with the concrete applied thereto.

Figure 2 is a longitudinal section on the line II—II of Figure 1, and

40 Figure 3 is a plan view of a section of a pavement or walk composed of a plurality of blocks made in accordance with this invention.

The blocks from which the pavement is 45 formed may be made in various sizes and shapes to suit requirements. For instance, certain of the blocks may be rectangular, as at 1 in Figures 1, 2 and 3, while others may be curved, as at 2 in Figure 3, to form straight and curved portions, respectively, 50 of a walk. As indicated in Figures 1 and 2, the rectangular blocks 1 are each composed of a frame 3, preferably of angle metal, although T-bars or other forms of metal bars may be used, if desired, said frames being 55 mitered at the corners, as at 4, and joined

together by corner brackets or knees 5. The frame bars are arranged so that each frame has a surrounding upstanding flange 6 and a bottom horizontal flange 7 extending around the same. The upstanding or vertical flange 6 serves to inclose a block or filling of concrete 8, while the horizontal flange 7 supports said concrete in the frame. 60

The concrete filling 8 preferably extends from the top edge of the frame 3 to the 65 bottom edge thereof, as shown in the right hand portion of Figure 2. Said frame may be reinforced or strengthened by any desired number of longitudinal strips 9 and transverse strips 10 secured to one another 70 and to the frame by brackets or knees 11. These reinforcing strips may be supported on the horizontal flange 7 of the frame and are preferably entirely covered by the concrete filling on the upper and lower surfaces 75 of the block. The concrete filling may be reinforced and further bound into the frame by wire mesh material 12 inserted in the pockets 13 formed between the longitudinal strips 9 and transverse strips 10 and frame 3. 80

The blocks made as just described as shown in the right hand portions of Figures 1 and 2 may be secured together end to end by angle tie bars 14 attached by means of 85 screw bolts 15, and when blocks are to be laid side by side as well as end to end T-bars or ties 16 may be employed. It will thus be seen that with blocks constructed in the desired dimensions and shapes, pavements or 90 walks may be quickly laid to meet any requirements, and in case alterations or moving of the pavement is afterwards necessary said blocks may be easily separated, taken up and relaid.

I claim:

1. A paving block comprising a frame having a plurality of transverse and longitudinal strips forming pockets, said frame having a marginal horizontal flange for supporting said strips, angle brackets connecting said strips in the corners of the pockets, reinforcing mesh material supported in said pockets on said brackets, and a filling of concrete in the frame covering said strips and reinforcing mesh material. 100

2. A portable pavement composed of concrete blocks, and inverted T-bars having horizontal base flanges extending below adjacent blocks and vertical flanges extending between adjacent blocks, said bars serving 110

for detachably connecting said blocks together end to end and side to side.

3. A portable pavement composed of concrete blocks each having an inclosing metal frame, and inverted T-bars having horizontal base flanges extending below adjacent blocks and vertical flanges extending be-

tween adjacent blocks, said bars being detachably fastened to said frames for connecting said blocks together end to end and side to side. ¹⁰

In testimony whereof I have signed my name to this specification.

JOHN NEWELL.
